UNITED STATES PATENT OFFICE.

WILLIAM A. ECKERT, OF BUFFALO, NEW YORK.

BOTTLE-STOPPER.

1,027,112.

Specification of Letters Patent.

Patented May 21, 1912.

Application filed September 15, 1910. Serial No. 582,141.

To all whom it may concern:

Be it known that I, WILLIAM A. ECKERT, a citizen of the United States, residing at Buffalo, in the county of Erie and State of New York, have invented certain new and useful Improvements in Bottle-Stoppers, of which the following is a specification.

This invention relates to an improved bottle stopper, which is adapted to be fitted 10 in a bottle in place of the usual cork, and when so inserted therein constitutes a spraying or sprinkling nozzle for the bottle.

The principal object of the invention is to produce a comparatively simple, cheap 15 and durable article of this class.

The invention also relates to certain details of construction of the device which will be hereinafter described and claimed, reference being had to the accompanying 20 drawings, in which,—

Figure 1 is a side elevation of the improved bottle stopper. Fig. 2 is a central vertical section through the improved stopper. Fig. 3 is a top plan view of the improved stopper. Fig. 4 is a bottom view of the improved stopper. Fig. 5 is a detached central section through the perforated metal top of the stopper. Fig. 6 is a detached central vertical section through the tubular 25 metal member of the stopper. Fig. 7 is a plan view of the same.

In referring to the drawings in detail, like numerals designate like parts.

This improved bottle stopper is designed 35 to be fitted in the opening in the neck of a bottle in place of the usual cork or stopper, and is provided with an enlarged perforated spraying or sprinkling head through the perforations of which the liquid within the 40 bottle is sprayed or sprinkled when the bottle is inverted.

The improved stopper, as shown in the drawings, consists of a top metal member 1 which is preferably of a convex shape and 45 is perforated, a metal tubular lower member and a cork annulus or ring 2 fitted around the lower end of the lower member. The metal tubular lower member has an upper tapering or bell shaped portion 3 50 which terminates at its lower end in an inwardly extending shoulder 4 and a lower tubular portion 5 which depends from the inner edges of the shoulder 4. The shoulder 4 extends nearly horizontal and is of a substantially annular form and the cork annulus or ring 2 is fitted upon the lower tubu-

lar portion 5 with its top surface against the shoulder 4. The lower tubular portion 5 is considerably smaller in diameter than the bell shaped portion 3 and in practice the lower end thereof may be made to flare, as 60 shown in Fig. 4, or may be otherwise enlarged to secure the cork ring thereon and prevent independent rotation of the cork ring on the lower tubular portion 5. 65

The metal parts of this improved bottle stopper are stamped, pressed or otherwise formed from suitable metal, such, for instance, as sheet aluminum; the perforated convex top member and the tapering or bell shaped lower member being formed to the desired shape in suitable dies and the top margin of the bell shaped portion 3 being bent inwardly upon the edge of the concavo-convex top, as shown in Fig. 2, thus rigidly 70 securing the two metal members of the stopper together.

The inwardly extending bent marginal edge or top flange of the bell shaped portion 3 is indicated in Fig. 2 by the numeral 80 6, and it will be observed by referring to said Fig. 2 that that portion of the upper part of the lower metal member lying between and connecting the outer termination of the flange 6 with the top termination of 85 the bell shaped portion 3 is substantially of a circular form having vertical outer and inner surfaces of appreciable width, as shown at 7 in said Fig. 2. This provides a fairly wide surface for the convenient grip for 90 the fingers of the operator when inserting the stopper in or removing it from the opening in the neck of the bottle.

The usual practice in fitting a stopper in or removing it from a bottle is to give it a 95 turning or twisting movement. With this improved stopper it will be noted that owing to the fact that the lower tubular member is formed in one integral piece of metal and has its upper portion shaped to fit 100 around the upper member and form a grasping portion for the fingers of the operator there is no possibility of a turning or twisting movement loosening or opening any joints between parts. 105

The principal advantage of this improved stopper resides in its simplicity, durability and cheapness which is due to the fact that the metal parts of the stopper are but two in number and that one of these 110 metal parts is so constructed that a cork annulus may be fitted on its lower portion

while its upper end is bent to form an exterior flange around the outer edge of the other part.

I claim,

- 5 A device of the class described consisting of a perforated top member having a downwardly extending vertical flange, a lower member having a tapering or bell shaped portion, a flanged top portion comprising
10 an upwardly extending vertical flange inclosing the vertical flange on said top member and an inwardly projecting horizontal flange engaging said top member, an inter-

mediate shoulder extending inwardly from the termination of the bell shaped portion and a lower reduced tubular portion depending from the inner termination of the intermediate shoulder, and a cork annulus fitted around the lower reduced tubular portion and having its upper annular edge against the intermediate shoulder.

WILLIAM A. ECKERT.
